UNITED STATES PATENT OFFICE.

PETER F. GREENWOOD, OF RICHMOND, VIRGINIA.

HORSESHOE-MACHINE.

SPECIFICATION forming part of Letters Patent No. 412,497, dated October 8, 1889.

Application filed May 1, 1889. Serial No. 309,187. (No model.)

To all whom it may concern:

Be it known that I, PETER F. GREENWOOD, a citizen of the United States, and a resident of Richmond, Henrico county, Virginia, have 5 invented certain Improvements in Horseshoe-Hammering Machines, of which the following is a specification.

The object of my invention is to construct a machine for hammering horseshoe-blanks 10 that will be simple and efficient and of few parts, as fully described hereinafter, reference being had to the accompanying drawings, in which—

Figure 1 is a side view of my improved 15 horseshoe-hammering machine. Fig. 2 is a plan view. Fig. 3 is a transverse section on the line 1 2, Fig. 1. Fig. 4 is a transverse section on the line 3 4, Fig. 1; and Figs. 5, 6, and 20 7 are enlarged views of the horseshoe-blank-holding mechanism.

A is the frame of the machine, on which is mounted the table B, carrying the horseshoe-blanks. This table slides on ways *a a* on the frame, and has a projection which passes 25 through a longitudinal slot in the frame. The table B is hollow in the present instance, and has two or more nipples, to one of which may be secured the inlet-hose and to the other the outlet-hose for the water, which acts to cool 30 the table during the working of the machine. Secured to the projection of the table B is a knee C, having a face *c*, against which acts the roller *d*, described hereinafter. This roller moves the table in the direction of the arrow, 35 Fig. 1. In the rear end of the table is secured a hook *e*, to which is fastened a chain or cord *e'*, which passes over a suitable pulley *e''* on the rear end of the frame of the machine, and to this cord is attached a suitable 40 weight *E* for returning the carriage to its original position, the carriage coming against suitable stops *a'*, having yielding buffers *a''* of rubber or other elastic material.

In bearings in the frame of the machine is 45 a shaft *F*, having two disks *D D'* secured to it, and tying these two disks together is a bolt *d'*, carrying the roller *d*, mentioned above. This roller is placed off center, as shown, so that as the shaft revolves the roller will force 50 the table in the direction of its arrow, Fig. 1, until it is released from contact with the

roller by the roller passing away from the knee. Immediately on its release the table will be brought back by the weight described to its original position. The shaft *F* is geared 55 to a shaft *D* by means of a gear-wheel *f* and pinion *f'*. The shaft *D* is in turn geared to a sleeve *H*, carried by the shaft *F* through the medium of a wheel and pinion *g g'*, this pinion *g'* being secured to the sleeve *H*, which 60 can either be secured to or form part of a driving-pulley *H'*. The driving-pulley may, as shown, be a combined fast-and-loose pulley or a plain pulley.

I I' are two housings, mounted on the frame 65 *A* of the machine, and these housings are provided with suitable bearings *i*, adjustable in said housings by means of a set-screw *i'*. The bearings support the shaft *J*, which has a driving-pulley *J'* on one side and carries 70 a frame *K*, in which are bearings for short shafts or spindles *K'*, carrying hammering-rolls *M*, which either revolve freely around the axle or shafts *K'* or are secured to the shafts which would revolve in the bearings 75 in the frame.

It may be mentioned here in the outset that the shaft *J* is speeded so as to allow the hammers *M* to strike the shoe in rapid succession while the shoe travels through the 80 machine slowly on the carriage or table *B*. On the table is a suitable die *N*, secured to said table by bolts *n*. This die can be removed and replaced by one of different size when circumstances require. On this die are 85 two projections *m m*, having their inner faces of the contour of the outside heel portion of the shoe. These projections extend to or nearly to the center of the shoe, as shown.

P P are two levers pivoted at *p*, and having arms *p' p''*. The arms *p'* are turned outward, as shown, and press against the inner heel portion of the shoe, while each arm *p''* has a roller *q*, which bears against a cam-face on a plate *Q*, which is adjustably secured to 95 the frame of the machine by bolts *r r*, which pass through slots *q'* in the said plates. Adjusting-screws *q''* bear against the back of the plates to set them up to the required point. Each cam-plate has a flat portion *s* and inclined 100 portions *s' s''*, one at the rear and the other at the front. The levers *P P* are kept against

these cam-faces by springs t t , secured to the pivots p , and bearing against pins or lugs t' on the arm t^2 of the lever.

When the carriage is in its normal position—that is, from under the hammer—the rollers on the levers P P rest in the depressions formed by the inclines on the cam-plates; but when the machine is going forward in the direction of the arrow, Fig. 1, and is under the hammer, the levers are pressed hard against the inside of the shoe, as shown in Fig. 2, holding the shoe fast, and the shoe is not released until the rollers on the levers are released, when they reach the inclines s^2 .

15 b is a projection which extends from the die directly back of the toe portion of the shoe, and enables the attendant to place the shoe in the right position on the die. In the die is a supplementary die T , having the 20 shape of the toe portion of the shoe, as shown in Figs. 2 and 5, and has portions u , which are beveled to give the required bevel to the 25 under side of the shoe.

The shoe hammered on this machine is a plain shoe, and creased and bent before hammering. In bending a creased shoe a portion of the material of the shoe is thrown up around the inner curve of the shoe, and this must necessarily be flattened, so that the face 30 of the shoe will be perfectly flat. To flatten this face is what this machine is intended for, and at the same time the necessary bevel is formed on the under side of the shoe, in order that the shoe may fit snugly to the horse's 35 hoof. This hammering also alters the inclination of the nail-holes to the angle required.

The shoe is removed from the machine automatically by the device which I will now describe.

40 Secured to one of the housings of the frame is a bracket V , through which passes a rod V' , a set-screw v on the bracket holding the rod securely after adjustment. On the end of the rod is a socket W , through which passes 45 the shank w of a head w' . This shank is adjustably secured by means of a set-screw w^2 or by a nut on the shank, or both. To the head W is pivoted a finger W' , beveled on the inner side and allowed to swing only in 50 one direction, as indicated by the arrow, a stop w preventing the swinging in the opposite direction. The finger is in such a position in respect to the shoe to be hammered that as the table moves forward and passes 55 under the hammer the shoe hits the finger, moving it up, the shoe passing under the finger sufficiently to allow the finger to drop to its normal position and back of the toe portion of the shoe. The shoe being released at 60 this point from the control of the levers P P

is held by the finger and prevented from returning with the table, and as soon as the table recedes the shoe will fall onto the inclined ribs A' , which direct it into a suitable receptacle or onto the floor.

65

I claim as my invention—

1. The combination, in a horseshoe-hammering machine, of the hammers, the traveling table carrying the horseshoes to be hammered, said table having a projection or 70 knee with which engages an arm on a disk or disks secured to a power-driven shaft, substantially as described.

2. The combination of the hammers, the moving table, mechanism for moving the 75 same, said table carrying the horseshoe, pivoted levers for holding the said horseshoe on the table, with cam-plates so cut as to hold the shoe as it passes under the hammer and to release the shoe at the end of both the forward and backward movement, substantially 80 as described.

3. The combination of the movable table having projections of the contour of the outside heel portion of the shoe, and having levers pivoted to said table, one arm of each of said levers pivoted against the inner portion of the shoe and the other arm bearing upon the cam-faces of the cam-plates, the 85 whole acting substantially as described. 90

4. The combination, in a horseshoe-hammering machine, of the traveling table, and the hammers, with a beveling-die situated on the table in a position directly under the front portion of the shoe to be hammered, so that 95 said shoe will receive the necessary inner bevel, substantially as described.

5. The combination of the table, the hammers, mechanism for operating the hammers and table, with a die for the shoe to be hammered, devices for retaining the shoe on the die with the finger pivoted to the head, so that the shoe to be removed can ride under said finger, but will be withdrawn on the return movement of the table, and devices for 100 releasing the shoe on its return movement, 105 substantially as described.

6. The combination, in a horseshoe-hammering machine, of the hammers with a traveling table carrying the shoe to be hammered, 110 said table having water-passages, substantially as and for the purpose set forth.

In testimony whereof I have signed my name to this specification in the presence of two subscribing witnesses.

PETER F. GREENWOOD.
